SPRAYER

Rudolph Bernhardt, Chicago, Ill.

Application March 1, 1937, Serial No. 128,441

4 Claims. (Cl. 299—97)

This invention relates to sprayers which may be used for various purposes but which are particularly intended for spraying lotions or emulsions such as wave sets or the like. These lotions are usually of a mucilaginous or slippery character. Consequently when applying the same to the hair the lotion gets on the hands of the operator and makes it difficult to handle the container holding the material. In accordance with the present invention I provide a container or bottle preferably having a relatively long neck and a sprayer having a handle portion arranged to cooperate with the bottle so that the device may be conveniently held and manipulated by one hand.

Other objects of the invention are to provide a sprayer including a container and having a handle portion for engagement with one finger of the operator and the spray nozzle held in adjusted position so that it may be actuated by the thumb; and to provide such other novel features and advantages as will appear more fully from the following description.

In the accompanying drawing illustrating this invention,

Figure 1 is a perspective view indicating the method of operating and holding the sprayer;

Figure 2 is an enlarged top plan view; and

Figure 3 is a sectional view of the sprayer head and bottle cap or support, taken on the line 3—3 of Figure 2.

In the particular form of sprayer shown in this drawing, 5 is the bottle or container having a neck portion 6 preferably of sufficient length so that it may be conveniently engaged by several fingers of the operator. As shown in Figure 1, the bottle has a cap 7 of the threaded type or other suitable type. The spray pump has a cylinder or tubular portion 8 with a downwardly extending intake pipe 9 and has a ring or flange 10 preferably formed integrally therewith, and a threaded upper end 11 which extends out through a hole in the top of the cap. A stiffening washer or disc 12 is preferably inserted between the flange or bead 10 and the cap.

45 A nut 13 engages with the threaded upper end of the cylinder and has an axial projection with a hole 14 of hexagonal or other suitable shape for receiving the hollow piston rod 15 which is slidably mounted therein. The piston rod is connected with a piston 16 which fits closely within the cylinder 8. The piston is normally held in raised position by a spring 17, the lower end of which rests on the end of the cylinder and the upper end engaging with a washer 18 fitting 50 against the lower end of the piston. This washer

has a hole 19 which serves as a valve seat for a ball 20, thus providing a check valve for the pump. A relatively light spring 21 is also provided for taking up any jar due to the quick outward movement of the piston under the influence of the 5 spring 17. The spring 21 is interposed between the upper end of the piston and the nut 13 as shown in Figure 3. The piston rod 15 has a spray nozzle or the like 22 secured to the upper end thereof and arranged at approximately right 10 angles thereto. This nozzle portion has a groove 23 in alignment with the nozzle discharge for receiving the thumb of the operator, which is used for actuating the sprayer. A handle 24 has a hole 15 at one end for receiving the threaded end 11 of the cylinder and is provided with an annular bead or ridge 25 for stiffening the same and for receiving a strengthening washer 26 which is interposed between the end of the handle and the nut or cap nut 13, the arrangement being such that when the 20 nut is tightened the handle may be held securely in any adjusted position circumferentially with respect to the spray nozzle. The handle may also be provided with additional ribs 27 for stiffening the same and terminates in a downwardly curved 25 end portion 28 which fits over the index finger of the operator as shown in Figure 1.

When an operator uses the sprayer the neck portion of the bottle is grasped by the fingers, for instance of the right hand, and the handle fits against the index finger as shown, which brings the thumb in alignment with the groove 23 so that the spray may be positively directed in the desired direction. By means of this arrangement the container or sprayer may be securely held 30 even if the hand becomes slippery due to contact with the lotion. If the operator is left-handed the handle may be adjusted relatively to the spray nozzle as shown in dotted lines in Figure 2, by loosening the nut and swinging the handle around 35 and again tightening the nut to hold the parts in such adjusted position.

Having thus described my invention, what I claim is:

1. The combination with a receptacle having a 45 relatively long neck adapted to be engaged by the hand, a cap for the receptacle, a spray pump mounted in the cap and having a discharge tube with a discharge nozzle at substantially right angles thereto, means for preventing the rotation 50 of the discharge tube in the cap, and a handle extending outwardly from the cap at substantially right angles to the outlet of the discharge nozzle and adapted to engage with the finger of the operator's hand while grasping the bottle, the 55

discharge nozzle being positioned to be engaged by the thumb of the operator's hand while supporting the bottle.

2. The combination with a bottle having an elongated neck providing a hand hold, of a cap for the bottle, a spray pump mounted in the cap and having a reciprocable spring actuated discharge pipe extending outwardly through the cap, with its discharge orifice at an angle to the axis 10 of the pipe, and non-rotatably mounted in the cap, a rotatable handle extending laterally from the cap and means for fastening the handle against rotation, the arrangement being such that when the bottle is held in the hand the handle will rest 15 on the fingers while the thumb may be used for reciprocating the discharge pipe whereby the spray may be discharged in a predetermined direction.

3. The combination with a bottle having a cap, 20 of a pump cylinder having a threaded end extending outwardly through a hole in the cap, an annular abutment on the cylinder on the inside of the cap, a nut engaging with the threaded end of the cylinder and having an axial projection 25 with a non-circular hole therethrough, a spring-pressed piston mounted in the cylinder, a reciprocable hollow piston rod extending outwardly from the piston through the hole in the projection, the periphery thereof conforming to the shape of the 30 hole whereby the rod is positively prevented from

rotating, a discharge nozzle at the end of the rod extending at right angles thereto and having a groove in the top, and a handle having a hole for receiving the threaded end of the cylinder and extending laterally from the cap, the handle being interposed between the nut and cap and held in adjusted position by tightening the nut. 5

4. The combination with a bottle having a cap, of a pump cylinder extending downwardly from the cap and having a threaded portion extended 10 upwardly through the hole in the cap, said cylinder having an integrally formed abutment, a washer interposed between the abutment and the inside of the cap, a handle having a hole for receiving the threaded end of the cylinder and having 15 an annular bead around the hole, a washer fitting within the bead, a cap nut engaging with the threaded end of the cylinder and coacting with the abutment to hold the parts in adjusted position, a piston in the cylinder, a spring tending 20 to hold the piston in raised position, a shock absorbing spring between the piston and the cap nut, said piston having a hollow rod of angular periphery extending outwardly through a hole in the cap nut shaped to conform to the rod to prevent 25 turning of the same, a discharge nozzle having a discharge portion extending at right angles to the rod and having a thumb recess in the top for receiving a thumb.

RUDOLPH BERNHARDT. 30
